CLAIM

The ornamental design for a shoe, as shown and described.

DESCRIPTION

FIG. 1 is a front perspective view of our shoe, according to our the design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines shown in the drawings, including the thin vertical broken lines shown on the upper edge of the midsole, represent portions of the shoe that form no part of the claimed design. The dot-dash lines in the drawings represent the bounds of the claimed design and form no part thereof. The longer, even-length broken lines within the shaded area of the shoe upper represent stitching that forms part of the claimed design. Areas of the design shown with a stipple fill illustrate a contrast in appearance.
